VAPOR GENERATOR

Robert V. Jones, Woodridge, Albert C. Foster, Westfield, and Edward R. Kilsby, Elizabeth, N. J., assignors to Foster Wheeler Corporation, New York, N. Y., a corporation of New York

Application May 13, 1943, Serial No. 486,810

16 Claims. (Cl. 122—491)

This invention relates to apparatus for the generation of vapor and, more particularly, to the separation of liquid and vapor in vapor generating apparatus having a vapor and liquid drum.

The invention provides a vapor and liquid drum having a plurality of weirs dividing the interior of the drum below the normal water line into separate sections, into one or more of which are discharged feed liquid and vapor and liquid, or liquid separated from a vapor and liquid mixture from vapor generating tubes. In one instance, the vapor flows from the aforesaid sections and is withdrawn from the drum, while the liquid separated from the vapor together with the feed liquid flows into another section from which it is passed to downcomer tubes for the vapor generating section or sections, thereby insuring vapor free liquid for the downcomers. Drums embodying the invention are of simplified construction and provide means for controlling the quality of vapor leaving the drum, for controlling the temperature of the liquid entering the downcomers, and for controlling the direction of circulation of the liquid in the drum. The liquid concentrate entering the downcomers of the vapor generating apparatus is also controlled and stratification of suspended solids in the liquid is prevented in drums constructed in accordance with the present invention.

The invention will be understood from the following description when considered in connection with the accompanying drawings forming a part thereof and in which:

Fig. 1 is a side elevational view of the vapor and liquid drum embodying one form of the invention;

Fig. 2 is a transverse sectional view taken on the line 2—2 of Fig. 1;

Fig. 3 is a longitudinal sectional view taken on the line 3—3 of Fig. 2, and

Fig. 4 is a plan view in section taken on the line 4—4 of Fig. 3;

Like characters of reference refer to the same or similar parts throughout the several views.

Referring to the drawings, the reference character 10 designates an elongated, steam and water drum, the opposite ends 11 and 12 of which are curved outwardly. The drum is supported on girders 13 mounted on supports 14. As shown, the interior of the drum is divided into three sections, an end section 15, an intermediate section 16, and an end section 17 by weirs 18 and 19. The weirs are substantially semi-circular to conform to the inner wall of the drum. Weirs 18 and 19 extend transversely of the drum and are

mounted on lugs 20 so that the periphery of each weir is spaced slightly from the inner wall of the drum. The space 20' between the periphery of each weir and the inner wall of the drum is of a dimension to permit the passage of only a small quantity of liquid therethrough. The weirs are longitudinally spaced in the drum and extend upwardly to a point short of the axis of the drum which point is beneath the normal water level WL. Lugs 20, to which the weirs are secured, are welded or otherwise fastened to the inner wall of the drum.

Feed water is introduced into the end portions 15 and 17 through a feed pipe 21 which extends longitudinally of the drum adjacent the bottom thereof. The pipe 21 passes through the weirs 18 and 19, and has a plurality of perforations 22 in the upper portion of the pipe in sections 15 and 17 so that feed water will be discharged into said sections. The feed pipe 21 is in communication with a source of feed water supply through a conduit 22 which is connected to the feed pipe substantially intermediate the opposite ends thereof.

25 Steam and water from one source of steam generation is discharged into the end sections 15 and 17 by the steam and water distributor conduit 23 which extends longitudinally through the drum adjacent the bottom thereof and passes through the weirs 18 and 19. The steam and water conduit 23 has a plurality of perforations 24 therein in the portion of said conduit in the sections 15 and 17 so that steam and water from the conduit 23 will be discharged into said sections.

30 Steam and water from the same or another source of steam generation is discharged into separators disposed in the upper portion of the drum adjacent the end compartments 15 and 17. The riser tubes 25 are connected to one side of the drum 10 adjacent end section 15 and above the normal water level WL. The separator 26 into which the tubes 25 discharge comprises an end member 27 on the end of the separator toward the interior of the drum and away from the adjacent end of the drum. One side edge of the end member abuts against the inner wall of the drum and the end member is secured to the drum by lugs 30. An impingement plate 29 is secured at the opposite ends thereof in spaced relationship to the inner wall of the drum by lugs 30. The impingement plate 29 extends between the discharge end of the tubes 25 and the interior of the drum so that the steam discharged from the tubes impinge against the plate 29. The 35 end member 27 closes the space between the plate

29 and the inner wall of the drum and the plate 29 extends outwardly at the top thereof to form a top portion 31 which abuts against the inner wall of the drum. In drums of great length, it may be desirable to omit the end plate 27. The impingement plate 29 projects below the normal water level WL so that water separated from the stream in the separator 26 will be discharged into the end section 15 and steam will enter the drum only through the open end of the separator. Riser tubes 32 are connected to the drum 10 at the opposite end of one side thereof adjacent to and above the end section 17. The riser tubes 32 discharge steam and water into a separator 33 which is similar to separator 26. Separator 33 comprises an end member 35 on the end of the separator toward the interior of the drum and away from the adjacent end thereof which member is secured to the inner wall of the drum by lugs 36. One side edge of the end member abuts against the inner wall of the drum. The steam and water discharged into the separator 33 impinges upon an impingement plate 37 which plate is secured at opposite ends thereof in spaced relationship to the inner wall of the drum by the lugs 36. The impingement plate 37 extends downwardly into the end section 17 of the drum to a point below the normal water level therein. The plate 37 extends outwardly at the top to abut against the inner wall of the drum. The separator is open at the end thereof adjacent the end of the drum. If desired, the end member 35 of the separator may be omitted.

The drum 10 has a steam outlet 39 in the central portion of the top thereof which outlet is in communication with a dry pipe 40. Dry pipe 40 is of usual construction comprising a longitudinally extending member 41 which is substantially U-shaped in cross-section and is closed at the opposite ends 42 and 43 and at the top thereof. Steam enters the dry pipe from the interior of the drum through a plurality of perforations 44 in the substantially flat top portion of said pipe. The dry pipe is secured to the interior of the drum by brackets 45. Downcomer connections 46 are in communication with the central section 16 of the drum at the bottom thereof.

As shown, the water in the drum is chemically treated in sections 15 and 17. The chemicals are delivered to the end sections by means of a chemical feed pipe 47 which extends longitudinally in the drum adjacent the feed pipe 21 and passes through the weirs 18 and 19, the chemicals being discharged from said feed pipe into the section 15 through the perforations 48 and into the section 17 through the perforations 49. The chemical feed pipe 47 is connected in the central portion thereof to a conduit 50 which is in communication with a chemical supply.

Water in the drum may be withdrawn for analysis through a sampling tube 51 in communication with a container 52 in the center compartment 16 of the drum. The container is held in position by brackets 54 secured to the inner wall of the drum and is adapted to receive water therefrom through the inlets 53.

In operation, steam and water from one steam generating source is discharged from the riser tubes 25 and 32 into separators 26 and 33 respectively. The steam and water discharged from said riser tubes impinges upon impingement plates 29 and 37 thereby separating the water and the steam. Separated water flows downwardly along the impingement plates 29 and 37 and from the separators 26 and 33 into the end sections 15

and 17 respectively. The steam separated from the water in the separator 26 flows from the separator at the open end thereof and impinges against the curved end 11 of the drum reducing the velocity of the steam. Impingement of the steam on the curved end section causes the steam to be subjected to centrifugal action thereby removing any moisture still entrained in the steam. The curvature of the end of the drum causes the direction of flow of the steam to be reversed while the separated moisture flows downwardly along the curved surface into the end section 15. The steam separated from the water in the separator 33 flows from said separator at the open end thereof and impinges against the curved end 12 of the drum causing a further separation of steam and water, the water passing into the end section 17 while the direction of flow of the steam is reversed by impingement against the curved end 12 of the drum. The steam from the separators 26 and 33, after impinging on the ends 11 and 12 respectively, flows in the space above the normal water level toward the center of the drum thence into the dry pipe 40 through the perforations 44 and outwardly of the drum through the outlet 39. Should the end members 27 and 35 of the separators 26 and 33 be omitted, which may be desirable particularly in a drum of great length, steam will flow from opposite ends of the separators into the space above the normal water level of the drum. The feed water, which enters the end sections 15 and 17 through the perforations 22 in the feed pipe 21, mixes with the highly concentrated mixture of separated water and feed water in the end sections. The water in the end sections 15 and 17, with the exception of a very small quantity which leaks beneath weirs 18 and 19, flows out of said sections over the top of the weirs and into the central section 16 thence outwardly of the drum through the downcomer connections 46. Steam entering the end sections 15 and 17 through the steam and water distributor pipe 23 is washed in the water in said sections and thereafter flows through the dry pipe 40 into the outlet 39. When the steam generating apparatus, of which the drum 10 is a part, is closed down and it is desired to drain the drum 10, the water in sections 15 and 17 drains beneath the weirs through the space 20 into the central section 16 thence outwardly thereof through the downcomer connections 46.

Although the invention has been disclosed as embodied in a steam and water drum adapted to receive steam from two sources of generation or two steam outlets from the same source, it will be understood that the invention may be used in a drum adapted to receive any form of vapor from but one source of generation or from one steam outlet of one source. It will also be understood that the drum may be constructed so that the riser tubes discharge into a separator positioned in the center of the drum which separator is adapted to discharge separated vapor and liquid into a central section thereof into which section the feed water is discharged. In such a construction, water will be withdrawn from the drum by downcomers in communication with the opposite end sections of the drum into which sections water from the central section flows. If desired, the drum may be divided into more than three separate sections by positioning more than two spaced weirs therein. Also, the drum may be constructed and arranged so that the weir plates divide the drum into longitudinally extending sections instead of transversely extending sec-

tions. The steam and water and the feed water would, as in the form of the invention shown, be discharged into some of the sections; the steam thereafter being passed from the drum and the water passed to another section or sections in the drum whence it flows into downcomers.

It will be understood that changes may be made in the form, location and relative arrangement of the parts of the apparatus shown and described herein without departing from the principles of the invention which is not to be limited excepting by the scope of the appended claims.

What is claimed is:

1. In a vapor and liquid drum, means beneath the normal liquid level in the drum dividing said drum into a plurality of sections, one of said sections having discharge means in communication therewith, vapor outlet means in communication with the drum above the normal liquid level therein, means for introducing feed liquid into another section, vapor and liquid separating means above the normal water level in the drum adjacent said other section and comprising a chamber having a discharge opening adapted to discharge vapor toward the end of the drum, said separating means having an impingement member therein and extending below the normal water level, and means for introducing a mixture of liquid and vapor into said separating means so as to impinge on said impingement member and thereby separate the liquid and vapor, the arrangement being such that the separated liquid flows from the impingement member into said other section and the liquid in the other section passes into said one section and is discharged therefrom through the discharge means, the vapor passing outwardly of the drum through the vapor outlet means.

2. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in communication with the intermediate section, vapor outlet means connected to the drum above the normal liquid level therein, means for introducing feed liquid into said end sections, and means for introducing liquid and vapor into the drum and delivering the liquid component of said mixture into the end sections, the arrangement being such that liquid flows from the end sections into the intermediate section and is discharged therefrom through said discharge means, the vapor passing outwardly of the drum through the vapor outlet means.

3. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in communication with the intermediate section, vapor outlet means connected to the drum above the normal liquid level therein, means for introducing feed liquid into said end sections, vapor and liquid separating means in the upper part of the drum above the normal water level therein adjacent each end section and adapted to discharge separated vapor into the drum and liquid

into said end sections, and means for introducing a mixture of liquid and vapor into the liquid and vapor separating means, the arrangement being such that the separated liquid flows into the end sections and the liquid in the end sections passes into the intermediate section and is discharged therefrom through said discharge means, the vapor passing outwardly of the drum through the vapor outlet means.

4. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, vapor outlet means connected to the drum above the normal liquid level therein, means for introducing feed liquid into said end sections, means for introducing liquid and vapor into the end sections, vapor and liquid separating means in the upper part of the drum above the normal water level therein adjacent each end section and adapted to discharge separated vapor toward the adjacent end of the drum and to discharge the liquid into said end sections, and means for introducing a mixture of liquid and vapor into the liquid and vapor separating means, the arrangement being such that liquid flows from the separating means into the end sections and the liquid in the end sections passes into the intermediate section and is discharged therefrom through said discharge means, the vapor passing outwardly of the drum through the vapor outlet means.

5. In a substantially horizontally extending vapor and liquid drum having end portions curved outwardly of the drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in communication with the intermediate section, vapor outlet means connected to the drum above the normal liquid level therein, means for introducing feed liquid into said end sections, vapor and liquid separating means in the upper part of the drum above the normal water level therein adjacent each end section, said means comprising a chamber having a discharge opening on the side thereof adjacent the end of the drum, an impingement member extending below the normal liquid level, and means for introducing a mixture of liquid and vapor into the separating means so as to impinge on said impingement member and thereby separate the liquid and vapor, the arrangement being such that liquid flows from the separating means into the end sections and the liquid in the end sections flows into the intermediate section and is discharged therefrom through said discharge means, the vapor passing into contact with the curved end portions of the drum thence outwardly of the drum through the vapor outlet means.

6. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in com-

munication with the intermediate section, vapor outlet means connected to the drum above the normal liquid level therein, a feed liquid conduit extending longitudinally of the drum and into said end sections and adapted to discharge liquid into the end sections, and means for introducing liquid and vapor into the drum and delivering the liquid component of said mixture into the end sections, the arrangement being such that liquid flows from the end sections into the intermediate section and is discharged therefrom through said discharge means, the vapor passing outwardly of the drum through the vapor outlet means.

7. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in communication with the intermediate section, vapor outlet means connected to the drum above the normal liquid level therein, a feed liquid conduit extending longitudinally of the drum and into said end sections and adapted to discharge liquid into the end sections, a conduit extending longitudinally of the drum and adapted to discharge a mixture of liquid and vapor into the end sections, vapor and liquid separating means in the upper part of the drum above the normal water level therein adjacent each end section and adapted to discharge separated vapor toward the ends of the drum and discharge liquid into said end sections, and means for introducing a mixture of liquid and vapor into the liquid and vapor separating means, the arrangement being such that liquid flows from the end sections into the intermediate section and is discharged therefrom through said discharge means, the vapor passing outwardly of the drum through the vapor outlet means.

8. In a substantially horizontally extending vapor and liquid drum, longitudinally spaced, transversely extending weirs in the lower part of the drum and extending upwardly to a point short of the normal liquid level in the drum, said weirs dividing the drum into an intermediate section and end sections adjacent opposite ends of said intermediate section, discharge means in communication with the intermediate section, vapor outlet means connected to the drum above the normal liquid level therein, vapor drying means through which the vapor passes in flowing to said outlet, a feed liquid conduit extending longitudinally of the drum and into said end sections and adapted to discharge liquid into the end sections, a conduit extending longitudinally of the drum and adapted to discharge a mixture of liquid and vapor into the end sections, vapor and liquid separating means in the upper part of the drum above the normal water level adjacent each end section, said means comprising a chamber having an impingement member therein extending below the normal water level in the drum, and a discharge opening in communication with the end section below the normal liquid level, and means for introducing a mixture of liquid and vapor into the separating means so as to impinge on said impingement member and thereby separate the liquid and vapor, the arrangement being such that liquid flows from the impingement member into the end sections and from the end sections into the intermediate section and is discharged therefrom through said discharge means, the

vapor passing outwardly of the drum through the vapor outlet means.

9. In a vapor and liquid drum, means for dividing the lower portion of the drum into a plurality of sections, means for delivering liquid to one section below the normal liquid level therein, means for delivering vapor to the drum, means for delivering the liquid component of a vapor and liquid mixture into said one section, the dividing means being constructed and arranged so that liquid in the one section flows from said section to another section in the drum at a substantial distance above the bottom of the drum, and means for separately withdrawing vapor from the drum and liquid from said other section.

10. In a vapor and liquid drum, means for dividing the lower portion of the drum into a plurality of sections, means for delivering liquid to one section below the normal liquid level therein, means for delivering vapor to the drum above the normal liquid level and adjacent said one section, vapor and liquid separating means disposed in the drum to receive said vapor and constructed and arranged to discharge separated vapor into the drum and separated liquid into said one section, the dividing means being constructed and arranged so that liquid in the one section flows from said section to another section in the drum at a substantial distance above the bottom of the drum, means for separately withdrawing liquid from said other section, and means for withdrawing vapor from the drum.

11. In a vapor and liquid drum, means for dividing the lower portion of the drum into a plurality of sections, means for delivering liquid to one section below the normal liquid level therein, means for delivering vapor to the drum above the normal liquid level and adjacent said one section, vapor and liquid separating means disposed in the drum to receive said vapor and constructed and arranged to discharge separated vapor into the drum and separated liquid into said one section, means for delivering a mixture of vapor and liquid to said one section below the normal liquid level therein, the dividing means being constructed and arranged so that liquid in the one section flows from said section to another section in the drum at a substantial distance above the bottom of the drum, means for separately withdrawing liquid from said other section, and means for withdrawing vapor from the drum.

12. In a vapor and liquid drum, means for dividing the lower portion of the drum into a plurality of sections, means for delivering liquid to one section below the normal liquid level therein, means for delivering vapor to the drum above the normal liquid level and adjacent said one section, vapor and liquid separating means disposed in the drum to receive said vapor and constructed and arranged to discharge separated vapor into the drum and separated liquid into said one section, means for conducting a liquid treating agent to said one section below the normal liquid level therein, the dividing means being constructed and arranged so that liquid in the one section flows from said section to another section in the drum at a substantial distance above the bottom of the drum, means for separately withdrawing liquid from said other section, and means for withdrawing vapor from the drum.

13. In a vapor and liquid drum, means beneath the normal liquid level in the drum dividing said drum into a plurality of sections, one of said sections having discharge means in communication

therewith, vapor outlet means in communication with the drum above the normal liquid level therein, means for introducing feed liquid into another section, vapor and liquid separating means above the normal water level in the drum adjacent said other section and comprising a chamber adapted to discharge vapor into the drum, said separating means having an impingement member therein and extending below the normal water level, and means for introducing 10 a mixture of liquid and vapor into said separating means so as to impinge on said impingement member and thereby separate the liquid and vapor, the arrangement being such that the separated liquid flows from the impingement member into said other section and the liquid in the other section passes into said one section and is discharged therefrom through the discharge means, the vapor passing outwardly of the drum through the vapor outlet means.

14. In a vapor and liquid drum, means beneath the normal liquid level in the drum dividing said drum into a plurality of sections, one of said sections having discharge means in communication therewith, vapor outlet means in communication with the drum above the normal liquid level therein, means for introducing feed liquid into another section, vapor and liquid separating means above the normal water level in the drum adjacent said other section and comprising a chamber having a discharge opening adapted to discharge vapor toward the end of the drum, said separating means having an impingement member therein, and means for introducing 30 a mixture of liquid and vapor into said separating means so as to impinge on said impingement member and thereby separate the liquid and vapor, the arrangement being such that the separated liquid flows from the impingement member into said other section and the liquid in the other section passes into said one section and is discharged therefrom through the discharge means, the vapor passing outwardly 40 of the drum through the vapor outlet means.

15. In a vapor and liquid drum, means beneath the normal liquid level in the drum dividing said drum into a plurality of sections, one of said sections having discharge means in communication therewith, vapor outlet means in communication with the drum above the normal liquid level therein, means for introducing feed liquid into

another section, vapor and liquid separating means above the normal water level in the drum adjacent said other section and comprising a chamber adapted to discharge vapor into the drum, said separating means having an impingement member therein and extending below the normal water level, the dividing means being constructed and arranged so that liquid in said other section flows therefrom into said one section at a substantial distance above the bottom of the drum to be discharged from said one section through the discharge means, and means for introducing a mixture of liquid and vapor into said separating means so as to impinge on said impingement member and thereby separate the liquid and vapor, the arrangement being such that the separated liquid flows from the impingement member into said other section, the vapor passing outwardly of the drum through the vapor outlet means.

16. In a vapor and liquid drum, means beneath the normal liquid level in the drum dividing said drum into a plurality of sections, one of said sections having discharge means in communication therewith, vapor outlet means in communication with the drum above the normal liquid level therein, means for introducing feed liquid into another section, vapor and liquid separating means above the normal water level in the drum adjacent said other section and comprising a chamber having a discharge opening adapted to discharge vapor toward the end of the drum, said separating means having an impingement member therein, the dividing means being constructed and arranged so that liquid in said other section flows therefrom into said one section at a substantial distance above the bottom of the drum to be discharged from said one section through the discharge means, and means for introducing a mixture of liquid and vapor into said separating means so as to impinge on said impingement member and thereby separate the liquid and vapor, the arrangement being such that the separated liquid flows from the impingement member into said other section, the vapor passing outwardly of the drum through the vapor outlet means.
